PROCESS FOR PURIFYING NAPHTHENIC ACIDS

Frederick J. Ewing, Pasadena, Calif., assignor to
Union Oil Company of California, Los Angeles,
Calif., a corporation of CaliforniaNo. Drawing. Application November 6, 1933.
Serial No. 696,914

12 Claims. (Cl. 260—514)

This invention relates to a process for treating naphthenic acids and it has particular relation to a process for treating these acids with some of the well known inorganic acids.

5 It is an object of my invention to present a simple and thoroughly satisfactory process for the removal of admixed carbonaceous material and dark color from crude or semi-refined naphthenic acids.

10 Naphthenic acids, such as might be obtained from the alkali wastes arising during the refining of petroleum or shale oil fractions, constitute a complex mixture of acidic compounds containing principally carbon, hydrogen and oxygen. They 15 range from comparatively low boiling liquids to materials which are solid or semi-solid at ordinary temperatures. Their viscosities as well as their boiling points are directly proportional to the viscosities and boiling points of the hydro-carbon fractions in which they were originally 20 present.

The crude naphthenic acids which are derived by acidifying alkali wastes formed during the treatment of hydrocarbon fractions contain varying amounts of carbonaceous materials. When 25 these crude naphthenic acids are freed from phenolic materials by careful acidification and distillation as hereinafter described, this quantity of carbonaceous materials appears to increase as a result of which 3 to 5% thereof and sometimes 30 even greater have been found to be present in the dephenolized naphthenic acids. The major portion of this carbonaceous material exists in a finely suspended or colloidal state, such that it is not removable by settling or centrifuging and 35 causes the naphthenic acids to be of a dark, turbid color, thereby rendering their sale as a commercial product practically impossible.

The term "alkali wastes", occurring above, is 40 meant to include the product which is obtained by treating with a caustic solution the extract resulting from a treatment of hydrocarbon fractions with liquid sulphur dioxide as well as any other alkaline wastes arising on refining of petroleum fractions.

45 It has been customary to distil the naphthenic acids to remove this admixed carbonaceous material and then treat the overhead product to remove the dark coloration and foul odor therefrom. This distillation was usually accompanied by a plugging of the still due to the presence of this undesirable material and the overhead product was not materially improved in color, i. e., not more than could be traced to the removal of 50 this carbonaceous material itself.

I have discovered that these carbonaceous materials and color bodies may be readily removed without distillation by contacting the crude or dephenolized acids which will be hereinafter designated as semi-refined acids, with oxygen-con-

taining inorganic acids, such as sulphuric acid, phosphoric acid, nitric acid, etc. When such acids are added in small amounts to naphthenic acids containing carbonaceous materials and the mixture agitated for a short time, the carbonaceous materials agglomerate to sufficiently large particles to permit separation by settling. It has furthermore been found that the naphthenic acids thus treated and which have subsequently been water washed and blown bright, possess an improved color, a slightly higher acid number than the untreated acids, are more fluid and can be distilled to a 95% overhead without coking the bottoms, whereas the untreated acids are black and opaque, are somewhat viscous and leave a coke-filled residue when distilled to 95% overhead. The acid treatment can conveniently, and sometimes preferably be carried out on naphthenic acids which have been diluted with light hydrocarbons in which case the sludge and carbon settles more rapidly, and in some cases more completely perhaps due to a sludge precipitating tendency of the light hydrocarbons in the latter instances. The light hydrocarbons may be subsequently removed by distillation or by extraction of the naphthenic acids with alkali. By the term "light hydrocarbons" I mean any low boiling hydrocarbon of either a paraffinic or aromatic nature and it includes normally volatile hydrocarbons, such as propane, butane, isobutane and perhaps pentane, low boiling hydrocarbon fractions, such as petroleum ether or cleaner's naphtha (a petroleum fraction boiling between 200-300° F.) and aromatic hydrocarbons, such as benzol. In general, the non-aromatic diluents have been found to be preferable.

The term "blowing bright", mentioned above, relates to the removal of finely suspended water from a hydrocarbon fraction by agitating the latter with hot air or a hot inert gas.

The concentration of the acid used in my process should be preferably such that the carbonaceous material and color bodies are precipitated as a granular mass. Acids of low concentration tend to emulsify the naphthenic acids whereas highly concentrated acids tend to be miscible with the naphthenic acids or else react with them.

Thus, where sulphuric acid having a concentration of 40% or less is used, a Pickering type of emulsion, apparently stabilized by the carbonaceous material, is obtained. These emulsions present considerable difficulty in their resolution and should be avoided. This emulsification trouble is substantially overcome where an acid of 50 55 50% concentration or over is used. Sulphuric acid of approximately 45% strength gave an emulsion which resolved on standing for a short time. Concentrations between 45% and 50% can be used under some conditions. The most de- 60

sirable range of concentration of sulphuric acid (or any of the other oxygen-containing acids) was found to be from 50% to approximately 83%. Acids substantially in excess of 85% tend to become miscible with the naphthenic acids and while some sludge separation will occur when they are contacted with the latter, the treating loss becomes such that the process is uneconomical.

10 Therefore, my invention may be said to reside in a process for purifying impure naphthenic acids which comprises treatment with oxygen-containing inorganic acids of well defined concentrations which treatment tends to remove the 15 suspended carbonaceous materials present in these naphthenic acids and at the same time tends to improve the color thereof as well as render them more susceptible to improvement in color on subsequent treatment, such as distillation.

20 My invention likewise extends to the treatment of naphthenic acids with any of the above identified inorganic acids in the presence of a low boiling hydrocarbon solvent whereby a more 25 rapid and efficient purification is brought about.

25 Although any oxygen-containing inorganic acid may be used for the purposes of my invention, I prefer to use acids such as sulphuric acid, nitric acid or phosphoric acid as they possess a very high degree of stability and are very 30 easily separable from the naphthenic acids after the purification has been completed.

35 Therefore, more specifically, my invention extends to the use for the purpose set out above of the class of oxygen-containing inorganic acids of well defined concentrations (if desired in the presence of a hydrocarbon diluent) which consists of sulphuric acid, nitric acid and phosphoric acid.

40 Considering the process in greater detail, a caustic liquor such as might be obtained by treating crude kerosene or a liquid sulphur dioxide extract thereof with sodium hydroxide is acidified in such a manner that it is only slightly acidic toward phenolphthalein. By so operating, the naphthenic acids, in contrast to the phenols, are not liberated from their alkaline metal salts (sodium phenolates) but remain as sodium naphthenates. The resulting mixture of 45 sodium naphthenates, phenols and admixed hydrocarbons is then steam distilled, if desired in the presence of a small amount of Edeleanu extract or an analogous liquid hydrocarbon, such as coal tar solvent-naphtha. This extract may 50 be the same as that from which the phenols and naphthenic acids were obtained by the above described acidification and neutralization. The function of this Edeleanu extract (or its obvious 55 equivalents) is to prevent frothing during the distillation of the mixture of sodium naphthenates, phenols and hydrocarbon oil. The distillation of this latter mixture, which is preferably carried out in the presence of steam, removes the phenols and hydrocarbon oils while the sodium naphthenates remain behind in the still. The sodium naphthenates remaining as a residue after distillation of the above-described mixture when dissolved in water and treated with sulphuric acid, produce naphthenic acids which 60 contain only very small amounts of phenols and admixed hydrocarbons. These crude naphthenic acids are of a poor color and contain considerable amounts of insoluble carbonaceous material. The major portion of this carbonaceous 65 material and color bodies which are present in

these crude naphthenic acids in amounts varying from 2 to 5%, or even higher, exists in a finely suspended or colloidal state such that it is not removable by settling or centrifuging and constitutes a serious objection in the marketing 5 or further refining of the dephenolized naphthenic acids.

These naphthenic acids are then treated with from $\frac{1}{2}$ to 10 volumes per cent of an oxygen-containing inorganic acid of suitable concentration, for instance, 60% sulphuric acid. The mixture is agitated for a brief period of time whereupon the carbonaceous materials tend to agglomerate to sufficiently large particles to permit separation by settling. By adding small amounts 10 of a "coking agent", such as water or siliceous earth immediately after agitation of the naphthenic acids with the sulphuric acid (or its equivalents) it is found that the separation of the sludge which comprises some free sulphuric acid 15 (or its equivalent) as well as the impurities which were present including all of the suspended carbonaceous material and most of the color bodies, is greatly facilitated. The thus refined naphthenic acids are separated from the sludge and 20 "coking" agent and are washed with water to remove any remaining inorganic acidity. They are subsequently blown bright, preferably with an inert gas. A material improvement in the color and acid number is brought about by this 25 treatment. Should any additional carbon precipitate out on standing, it may be removed by a simple filtration, for instance through sand or any inert filtering material. When the so purified naphthenic acids are distilled, an excellent product having a bland odor and a stable 30 color of from 2 to 3 N. P. A. is obtained.

35 The separation of the sludge and carbonaceous materials in the above described separation may be materially improved by diluting the impure naphthenic acid charge before acid treatment with an equal volume of a hydrocarbon diluent of the nature described above. In cases where such a diluent has been employed, the latter is separated from the sludge and carbonaceous 40 materials together with the naphthenic acids and may be removed therefrom by simple distillation or by extracting the naphthenic acids with alkali and acidifying (with an inorganic acid) the alkaline extract.

45 As a modification of the above-described method of operation in which special precautions were taken for the removal of the phenols from the naphthenic acids, I may add a sufficient amount of an inorganic acid to any of the alkaline 50 wastes referred to above to liberate the phenols together with the naphthenic acids. Such a method of operation is deemed applicable in cases where the presence of phenolic materials together with the naphthenic acids is not undesirable.

55 The naphthenic acids, obtained by this method, contain in addition to the phenols which are completely soluble therewith definite amounts of substantially the same carbonaceous materials 60 which were present in the dephenolized naphthenic acids.

65 The removal of these materials may be carried out in a manner identical to the one described 70 in connection with the naphthenic acids which had been substantially freed from phenolic materials.

75 The following examples are illustrative of the process of my invention.

Example I

A charge of 1500 cubic centimeters of semi-refined naphthenic acids was air agitated for 15 minutes with 80% sulphuric acid. Just before the acid agitation was stopped, 5 grams of diatomaceous earth were added to facilitate the coagulation of the sludge. The sludge (which contained only small amounts of naphthenic acids) was removed from the supernatent naphthenic acids and the latter were washed with hot salt water; after removal of the wash water, they were blown bright with natural gas at a temperature of approximately 180° F.

The bright naphthenic acids had an organic acidity of 290 milligrams of KOH per gram of substance, as compared with an acid number (organic acidity) of 284 milligrams of KOH for the original semi-refined acids. They were, without filtration, transparent when viewed through the neck of a four ounce oil sample bottle, whereas the unrefined acids were black and had no such transparency. The refined naphthenic acids also possessed a much larger degree of fluidity than the crude product and were free from admixed carbonaceous material.

The purified acids were then subjected to a distillation and a product was obtained which had the following properties:

Acid number—297 milligrams of KOH per gram of substance.

Color—2 to 2½ N. P. A.

Odor—Sweet.

A distillation, similar to the one described above was made on the semi-refined acids before acid treatment and the following observations were made:

(1) The semi-refined acids exhibited a tendency to plug up the outlet of the still.

(2) The overhead product from the acid treated naphthenic acids was of a very much lighter color than that of the non-treated acids.

(3) The acid treated naphthenic acids could be distilled without cracking to a 97% overhead (593° F. vapor temperature), while cracking occurred with the non-acid treated acids at 92% overhead (586° F. vapor temperature).

(4) The bottoms from the acid treated naphthenic acids were still fluid when cooled; those from the untreated acids were fairly hard in consistency.

Example II

The following table illustrates the effect of the adding of a hydrocarbon diluent and of the amount of 60% sulphuric acid on the time necessary for sludge coagulation:

60	Semirefined naphthenic acids in ml.	Cleaners' naphtha, ml.	80% H ₂ SO ₄ , ml.	Agitation number of shakes	Time for sludge to settle to compact mass
65	50	50	5	150	10 sec.
	50	25	5	150	30 sec.
	50	15	5	150	1 min.
	50	0	5	150	15 min.
	50	50	4	150	30 sec.
	50	50	3	150	1 min.
	50	50	2	150	3 min.
	60	50	1	150	5 min.
	50	0	3	150	20 min.
	50	0	2	150	30 min.

This table is indicative of the fact that larger quantities of the sulphuric acid used (60%) tend to decrease the time of settling and also that an increase in the amount of solvent for the same

amount of acid tends to bring about a more rapid coagulation of the sludge.

The amount of hydrocarbon diluent to be used in facilitating the separation of the coagulated carbonaceous material will be obvious to those skilled in the art. Although an amount equal to that of the naphthenic acid charge to be treated has been found practical in a number of instances, greater or lesser amounts may be necessary or convenient under certain conditions. It has been observed that where the volume of hydrocarbon diluent added is greater than that of the naphthenic acid charge, a better color is obtained with the same amount and strength of acid.

Other "coking" agents than the clay, previously referred to, may be used. Thus, small amounts of water may be added to the naphthenic acid mixture immediately after agitation with the sulphuric acid or its equivalents. However, "coking" agents of the nature of clay or siliceous earth are preferred as the naphthenic acids appear to have a somewhat brighter color when the non-aqueous "coking" agent is used.

The distillation of the naphthenic acids from which the carbonaceous materials have been removed may be dispensed with if so desired. Although this distillation will improve the color thereof, they are nevertheless of such quality that they may be readily marketed as a commercial product.

Although this process has been particularly described in connection with naphthenic acids admixed with carbonaceous materials, it has been found that naphthenic acids which are free from these materials or only substantially so, may be materially improved thereby. In such cases, the refining action brought about by this process seems to reside principally in an improvement in odor, color and acid number of the naphthenic acids treated.

The naphthenic acids obtained by the process herein described are of such a purity that they may be readily used for commercial products, such as cosmetics, soaps, emulsifying agents, etc.

Instead of using an Edeleanu extract or coal tar solvent naphtha for the prevention of frothing during distillation of the mixture of sodium naphthenates, phenols and hydrocarbon oil in which process the phenols are removed, I may use any organic solvent preferably of an aromatic nature having a distillation range substantially that of the other solvents set out above.

While only nitric, sulphuric and phosphoric acids have been disclosed as examples of oxygen-containing inorganic acids, it has been found that all oxygen-containing inorganic acids are capable of bringing about the purification of the naphthenic acids herein set forth. Thus, oxygen-containing inorganic acids other than those set out above, such as chloric, (HClO₃), bromic (HBrO₃), and iodic acids (HIO₃) may be used for the removal of carbonaceous materials or color bodies or both from naphthenic acids in which they are present.

This invention is not limited to any specific example herein set forth nor to naphthenic acids derived from any particular hydrocarbon fraction as all naphthenic acids derived from any source, may be refined thereby. As to the scope of this invention, reference is made to the appended claims.

I claim:

1. In a process for purifying naphthenic acids containing admixed carbonaceous materials, the

- steps of contacting said acids with sulphuric acid having a concentration between 45 and 85% and separating the naphthenic acids from the acid sludge and the carbonaceous materials which have been agglomerated by the aforesaid sulphuric acid.
2. In a process for purifying naphthenic acids contaminated with carbonaceous materials and color bodies, the steps of contacting said acids with sulphuric acid having a concentration of 80% and separating the naphthenic acids from the acid sludge and the carbonaceous materials and color bodies which have been agglomerated by the aforesaid sulphuric acid.
3. In a process for purifying naphthenic acids contaminated with carbonaceous materials, the steps of contacting said acids with phosphoric acid having a concentration which is in excess of 40% and separating the naphthenic acids from the acid sludge and the carbonaceous material which has been agglomerated by the aforesaid phosphoric acid.
4. In a process for purifying naphthenic acids contaminated with carbonaceous materials, the steps of contacting said acids with an oxygen-containing, inorganic acid of such strength that it is adapted to agglomerate the aforesaid carbonaceous materials, adding a "coking" agent to said mixture of naphthenic and oxygen-containing, inorganic acid and separating the naphthenic acids from the agglomerated carbonaceous materials, acid residue and coking agent.
5. In a process for purifying naphthenic acids contaminated with carbonaceous materials, the steps of contacting said acids with an oxygen-containing, inorganic acid of such strength that it is adapted to agglomerate the aforesaid carbonaceous material, adding a "coking" agent to said mixture of naphthenic acids and the oxygen-containing, inorganic acid, separating the naphthenic acids from the agglomerated carbonaceous materials, acid residue and coking agent, and washing the separated naphthenic acids with a reagent adapted to remove any residual inorganic acidity therefrom.
6. In a process for purifying naphthenic acids according to claim 5, the additional steps of distilling the naphthenic acids which are free from inorganic acidity and condensing the overhead product.
7. A process for obtaining naphthenic acids of excellent color and which are free from admixed carbonaceous materials and color bodies comprising the steps of extracting a petroleum fraction with alkali, treating the resulting extract with an inorganic acid in such a manner that only the phenols admixed with the alkali naphthenates in the aforesaid extract are liberated, distilling the phenols overhead, liberating the free crude naphthenic acids from the alkali naphthenates remaining in the still after completion of the said distillation for removal of the phenols by adding an inorganic acid to the said naphthenates, separating the free naphthenic acids which contain admixed carbonaceous materials, contacting said free naphthenic acids with $\frac{1}{2}$ to 10% by volume of an oxygen-containing, inorganic acid of such strength that it is adapted to agglomerate the aforesaid carbonaceous materials and separating the naphthenic acids from the agglomerated carbonaceous materials and acid residues.
8. A process for obtaining naphthenic acids of excellent color and free from admixed carbonaceous materials according to claim 7 in which the acid used is sulphuric acid of a concentration of more than 45% and less than 85%.
9. A process for obtaining naphthenic acids of excellent color and free from admixed carbonaceous materials which comprises extracting a petroleum fraction with alkali, acid treating the resulting extract to liberate a mixture of impure naphthenic acids, separating the impure naphthenic acids which contain the aforesaid carbonaceous materials, contacting the said impure naphthenic acids with an oxygen-containing, inorganic acid selected from the class consisting of sulfuric acid, phosphoric acid and nitric acid of a concentration between approximately 50% and 83% to agglomerate the aforesaid carbonaceous materials and separating the naphthenic acids from the agglomerated carbonaceous materials and acid residue.
10. A process for obtaining naphthenic acids of excellent color and which are free from admixed carbonaceous materials, comprising the steps of extracting a petroleum fraction with alkali, treating the resulting extract with an inorganic acid in such a manner that only the phenols admixed with the alkali naphthenates in the aforesaid extract are liberated, distilling the phenols only from the alkali naphthenates, liberating the free crude naphthenic acids from the alkali naphthenates remaining in the still after completion of the said distillation for removal of the phenols by adding an inorganic acid thereto, separating the free naphthenic acids which contain admixed carbonaceous materials, diluting said acids with a low boiling hydrocarbon fraction, contacting the diluted acids with $\frac{1}{2}$ to 10% by volume of an oxygen-containing, inorganic acid of such a strength that it is adapted to agglomerate the aforesaid carbonaceous materials, adding a "coking" agent to the acid mixture formed by contacting the diluted naphthenic acids with the aforesaid oxygen-containing, inorganic acid, separating the naphthenic acids and hydrocarbon diluent from the agglomerated carbonaceous materials, acid residue and coking agent, washing the separated naphthenic acids with a reagent adapted to remove any residual inorganic acidity therefrom, separating the naphthenic acids and hydrocarbon diluent from the washing agent, distilling off the hydrocarbon diluent from the said naphthenates and finally distilling the naphthenic acids.
11. In a process for purifying naphthenic acids contaminated with carbonaceous materials, the steps of contacting said acids with an oxygen-containing inorganic acid of the class consisting of sulphuric acid, nitric acid and phosphoric acid of a concentration between approximately 50% and 83%.
12. A method as claimed in claim 4 in which the inorganic acid is concentrated sulfuric acid.

FREDERICK J. EWING.
